Application June 3, 1950, Serial No. 10,335

Term of patent 7 years

(Cl. D86—8)

To all whom it may concern:

Be it known that I, Max Rosedale, a citizen of the United States and a resident of New York city, in the county of Bronx and State of New York, have invented a new, original, and ornamental Design for a Comb or Similar Article, of which the following is a specification, reference being had to the accompanying drawing, forming part thereof.

In the accompanying drawing:

Figure 1 is a side view of a comb or a similar article embodying my new design.

I claim:

The ornamental design for a comb or similar article, substantially as shown.

MAX ROSEDALE.
